UNITED STATES PATENT OFFICE

CLEMENT L. DORLAND, OF BAKERSFIELD, CALIFORNIA

AIR CONDITIONER

Application filed November 6, 1931. Serial No. 573,445.

This invention relates to improvements in air conditioners and has particular reference to a device wherein air may be effectively cooled through the use of water without adding moisture to the air being conditioned.

A further object is to produce a device which is simple in construction and takes up a minimum amount of space.

A further object is to produce a device which is relatively quiet in its operation.

A still further object is to produce a device which is economical to manufacture.

Other objects and advantages will be apparent during the course of the following description.

In the accompanying drawings forming a part of this specification and in which like numerals are employed to designate like parts throughout the same,

Fig. 1 is a vertical cross section taken on the line 1—1 of Figs. 2 and 3;

Fig. 2 is an end elevation looking from the right-hand end of the drawing of Fig. 1;

Fig. 3 is an end view looking from the left-hand end of Fig. 1, and

Fig. 4 is an enlarged detail cross sectional view of a spray nozzle.

In conditioning air it is customary to blow a current of air through a spray of water so as to reduce the temperature of the air through the evaporating of a certain proportion of water. This results in the air leaving the device with a very heavy moisture content which is often detrimental to the health of the persons breathing this air. Applicant has therefore devised an air cooler wherein the evaporation takes place, through the mixing of air and water, and this cooling caused by evaporation, transmits its effect to air which is kept out of contact with the water.

In the accompanying drawings wherein for the purpose of illustration is shown a preferred embodiment of my invention, the numeral 5 designates a base upon which is mounted an outer shell 6 within which is positioned an inner shell 7. The shell 7 is spaced from the shell 6 as illustrated in Figs. 1 and 2. The shell 6 has a guard 8, while the shell 7 has a guard 9. A partition 11 extends between the shell 6 and shell 7 and prevents

circulation of air therebetween, except in a definite path.

An end plate 12 is fitted to one end of the shell 7 and serves to support the ends of pipes 13. These pipes extend parallel to the shell 7 and have their ends bent so as to connect with the shell 7, as indicated at 14. At 16 I have shown a motor having a shaft 17, which is journaled as at 18 in the plate 12. A fan 19 is secured to the shaft 17 at a point adjacent the guard 9. A fan 21 is also secured to the shaft 17 at a point adjacent the guard 8. A water pipe is shown at 22, which has a suitable valve 23 and a nozzle 24. The nozzle 24 may be of any desired construction, and is so arranged that a spray of water issuing therefrom will be encountered by the blades of the fan 19, and blown over the pipes 13 toward the plate 12.

Openings 26, in the bottom of the casing 7, permit air to be drawn in by the fan 19 as well as the water from the spray draining into a telescoping or extensible discharge pipe 27, which discharge pipe may lead to any suitable outlet so that the moisture laden air and water will be removed from the room. It will therefore be apparent that the air to be cooled will enter the space A, pass into the ends 14 of the pipes 13 and during the passing through these pipes this air will be cooled through the effect of evaporation, will be discharged by the fan 21 and the water and air passing over these pipes will be drained out into the pipes 27 and discharged out of the room while the cool air will take the path 85 as indicated by the arrows, at the extreme left of the drawings.

It will thus be seen that I have produced a device which will accomplish all the objects above set forth.

It is to be understood that the form of my invention herewith shown and described is to be taken as a preferred example of the same and that various changes relative to the material, size, shape and arrangement of parts may be resorted to without departing from the spirit of the invention or the scope of the subjoined claims.

Having thus described my invention, I claim:

1. In a device of the character described, a pair of spaced shells defining a passageway for the passage of air therethrough, a shaft extending through said shells, fans secured to said shaft and the opposite ends thereof, a plate secured to one of said shells, pipes extending through said plate, whereby air may be drawn through said pipes by one of said fans the other of said fans forcing air over said pipes.
- 10 2. In a device of the character described, a pair of spaced shells defining a passageway for the passage of air therethrough, a shaft extending through said shells, fans secured to said shaft and the opposite end thereof, a plate secured to one of said shells, pipes extending through said plate, whereby air may be drawn through said pipes by one of said fans, and means for discharging a fluid over the exterior of said pipes through the action of one of said fans, said last mentioned fan also forcing air over said pipes.
- 15 3. In a device of the character described, an outer shell having a forwardly formed guard thereon, an inner shell spaced from said first mentioned shell and having a rearwardly formed guard thereon, said inner shell having a plate secured to one end thereof, a shaft extending through said plate and axially arranged in said inner shell, a pair of fans secured to said shaft at points adjacent said guards, and means for rotating said shaft, a nozzle positioned within said inner shell and adapted to conduct a spray of water against one of said fans, and pipes secured to said plate and having their opposite ends curved and connected to said inner shell at the rear portion forming an air intake.
